UNITED STATES PATENT OFFICE.

ABRAHAM NEWMAN, OF CHICAGO, ILLINOIS.

DESIGN FOR A BOX FOR PATROL-STATIONS.

SPECIFICATION forming part of Design No. 33,514, dated November 6, 1900.

Application filed July 28, 1900. Serial No. 26,201. Term of patent 14 years.

To all whom it may concern:

Be it known that I, ABRAHAM NEWMAN, a citizen of the United States of America, and a resident of Chicago, county of Cook, State 5 of Illinois, have invented and produced a new and original Design for a Box for a Patrol-Station, of which the following is a specification.

In the accompanying drawings, Figure 1 is 10 a perspective view showing the upper front portion. Fig. 2 is a perspective view showing the opposite end and the bottom and rear, and Fig. 3 is an end elevation.

In the said drawings, A is the body of the 15 box, which is in the form of a quadrant of a cylinder.

B is a cover extending over the convex por-

tion of said box and provided with lips B', which overlap the ends of the box.

In one end of the box there is a key-opening 20 D, and on the back of the box are the projections or lugs F.

The leading features of my design consist of the quadrant-shaped box, the convex cover B of which is provided with the lips B'. 25

What I claim is—

The design for a box for a patrol-station as herein shown and described.

Signed by me at Chicago, Illinois, this 7th day of December, 1899.

ABRAHAM NEWMAN.
